SPINNING APPARATUS

Edward J. Abbott, Wilton, N. H., assignor to
 Abbott Machine Company, Wilton, N. H., a corporation of New Hampshire

Application December 29, 1933, Serial No. 704,434

5 Claims. (Cl. 118—10)

This invention relates to spinning apparatus and has for its principal object to provide efficiently for breaking the thread on the occurrence of so-called "false spinning" in ring spinning machines.

The balloon of spinning yarn approaching the traveler of a spinning ring is in the form of a spiral, which under certain conditions tends to collapse and form two small balloons with a node therebetween. The collapse of the balloon is conducive to the yarn catching on the spinning package or bobbin and winding thereon without passing through the traveler, this occurrence being known as "false spinning". In the use of a bobbin having a top head, false spinning may result in winding a bunch of hard twisted yarn immediately below the top head of the bobbin. This bunch must be cut off before the yarn can be pieced up and spinning resumed, which causes waste of material and increases the idle time of the spindle. In addition the hard-twisted waste material thus produced and cut off is not worth as much as the soft waste produced by a normal breakdown in which the sliver winds around one of the draft rolls without being twisted. The present invention remedies this by providing for breaking the thread almost immediately whenever false spinning occurs.

My copending application, Serial No. 460,130, now Patent No. 1,960,403, discloses that certain relations between length of balloon and length of spinning package will tend to prevent collapse of the balloons and false spinning throughout the machine. Nevertheless, it is desirable to provide for breaking the appropriate individual thread in case false spinning should take place on any one of the many spinning bobbins of a machine, due for example to some inequality or defect in the thread being spun onto the particular bobbin in question.

In the accompanying drawing the invention is shown by way of example as applied to a ring spinning machine having certain characteristics of the invention of my said application, Serial No. 460,130, it being understood, however, that the invention is of general applicability in ring spinning, and may be of greater utility when applied to machines wherein there is a greater likelihood of false spinning than in the machine of my said application.

In the drawing,

Fig. 1 is a fragmentary front elevation of a portion of a spinning frame containing the improvement of the present invention;

Fig. 2 is a fragmentary front elevation indicat-

ing especially the course of the strand when the ring-rail is at its highest position;

Fig. 3 is a vertical section taken on the line 3—3 of Fig. 1, with the outline of the bobbin shown in dotted lines; and

Fig. 4 is a horizontal section on line 4—4 of Fig. 3.

Referring to Fig. 1, the strand B is shown as coming from front delivery rolls 8 and 9, through a pot eye or guide 12, and thence in a balloon 10 formation to the traveler 18 which runs on the ring 17 on the traversing ring-rail 6. Each rotatable strand receiver, such as a bobbin 7, is shown as separated from its neighboring receiver by a stationary separator plate 20 fastened by means of lugs 21 to a stationary rail 10. As disclosed in my said copending application, the separator plates 20 can extend from the thread board 11, down to below the bottoms of the bobbins, preferably extending through slots 19 in the ring-rail.

The traveler 18 controls the size of the balloon during normal spinning. In the lower positions of the ring-rail, the spinning balloon may contact to some extent with the separator plates 20, but as the ring-rail rises the balloon becomes shorter, and less outwardly bowed, and with the ring-rail at about the level of the bobbin top as in Fig. 2 there is no contact of the normal balloon with the separator plates, the primary utility of the upper portions of the separator plate being to prevent broken ends of thread from whipping out into contact with neighboring spinning threads. Thus it will be observed that around and adjacent to the upper part of the receiver there is a sizeable space into which the ballooning thread does not enter during normal spinning.

The means for breaking the thread on the occurrence of false spinning may for example take the form of a strand-catching hook 31 in this zone outside of the path of the normally ballooning thread but in position to catch the differently-shaped balloon resulting from false spinning. As herein illustrated, the hook 31 is located adjacent to the level of the top head of the bobbin, at which level of winding the tension afforded by the traveler normally maintains the yarn in a relatively straight path from the pot eye to the traveler. However, in the event that the balloon collapses in the lowermost position of the traveler, is caught by the winding package and begins to wind near the head of the bobbin without passing through the traveler, the balloon thus formed is uncontrolled by the traveler and is consequently abnormally wide for its

height, contacting the separator plates in the zone of the hooks 31. A balloon of such configuration, indicated at B' in Fig. 1, is thus caught by the hook 31 and accordingly broken, thus effectively stopping false spinning.

Preferably the hook 31 is formed of a simple piece of wire inserted through two holes in the separator plate, with one end clinched down at 31a and another longer end 32a extending in position to catch the balloon produced by false spinning.

Obviously the exact location of the strand-catching means, such as hook 31, will depend upon the shapes of the normal balloons, being placed out of the path of any normal balloon, but in a position to catch the false-spinning balloon which is uncontrolled by the traveler.

I claim:

1. Spinning apparatus comprising a rotatable strand receiver, and a cooperating ring and traveler, a separator plate adjacent to the ring, and a hook on said separator plate at a point not normally contacted by the ballooning strand and in position to catch the enlarged balloon resulting from false spinning.
2. Spinning apparatus comprising a rotatable strand receiver, and a cooperating ring and traveler, a separator plate adjacent to the ring, and a hook mounted on the separator plate at a

point not normally contacted by the ballooning strand and in position to detain a ballooning strand that strikes the separator plate at a point higher than in normal spinning.

3. Spinning apparatus comprising a rotatable strand receiver, and a cooperating vertically traversing ring and traveler, a separator plate adjacent to the ring, and a hook mounted on the separator plate adjacent to the upper limit of traverse of the ring. 10

4. Spinning apparatus comprising a rotatable strand receiver and a cooperating ring and traveler, a separator plate positioned to confine a ballooning strand which is winding onto the top of the receiver without passing through the traveler, and a hook mounted on the separator plate at a level to detain such ballooning strand without catching a normally ballooning strand. 15

5. Spinning apparatus comprising a rotatable strand receiver, and a cooperating ring and traveler, a separator plate adjacent to the ring, and strand-catching means on said separator plate extending from the plate toward the axis of rotation of the strand receiver at a point not normally contacted by the ballooning strand and 20 in position to catch the enlarged balloon resulting from false spinning. 25

EDWARD J. ABBOTT.
